UNITED STATES PATENT OFFICE.

PEHR CHRISTIANSSON, OF CARLOS, MINNESOTA.

INCUBATOR.

Application filed January 18, 1923. Serial No. 613,383.

To all whom it may concern:

Be it known that I, PEHR CHRISTIANSSON, a citizen of the United States, residing at Carlos, in the county of Douglas and State 5 of Minnesota, have invented a new and useful Improvement in Incubators, of which the following is a specification.

My invention relates to incubators, and its general object is the provision of an improved structure by means of which the handling of the eggs for the purpose of turning and cooling the same may be accomplished with a minimum amount of time and labor.

15 A more specific object is the provision of a drawer for containing the eggs which may be withdrawn for the purpose of cooling the same without removing the eggs therefrom, the drawer being also provided 20 with a plurality of individual trays which are revolvably mounted and provided with means whereby the same may be simultaneously revolved for turning all of the eggs from the outside of the incubator in a 25 moment's time.

With the above and other objects in view, the invention consists in certain details of construction, the preferred form of which is illustrated in the accompanying drawings.

30 In the drawings:—

Fig. 1 is a perspective view of an incubator equipped with my invention.

Fig. 2 is a perspective view of the front part of the same with the drawer extended.

35 Fig. 3 is a plan view of the drawer with parts shown in section.

Fig. 4 is a longitudinal vertical section through the drawer.

40 Fig. 5 is a vertical transverse section through the incubator.

Fig. 6 is a side elevation of the lamp support with the adjacent part of the incubator shown in section.

45 Fig. 7 is a perspective view of the end of one of the trays.

The incubator of which my invention forms a part comprises a rectangular body portion 1 supported by the usual legs 2, and provided with a heating system 3, which is 50 preferably of the hot water type. The water is heated in the usual manner by means of a lamp 4 which is supported beneath a flue 5 around which extends a water jacket. The operation of the lamp and the 55 amount of heat which is transmitted to the

incubator is controlled by means of a damper 6, the position of which is determined by means of an arm 7 which is actuated by means of a thermostat 8.

Instead of the usual egg trays, which must be removed through a hinged door, in order to cool or turn the eggs, I have provided the incubator with a slideable drawer 9 which extends substantially throughout the length and breadth of the body 1, and is provided at its front side with a window 10 and drawer pulls 11. The drawer may be extended as shown in Fig. 2 for the purpose of cooling the eggs, or for inserting or removing the same from the trays. A button 12 or the like may be provided for locking the drawer in closed position, as shown in Fig. 1.

Since the drawer is of considerable length, and in order to cool all the eggs equally or to gain access to all of the trays it is necessary to completely extend the drawer, I have provided means for supporting the same when in its extended position. This means includes a bail 13 which is pivotally supported by eyes 14 secured in the upper front edge 80 of the incubator. When the drawer is fully extended, the bail is adapted to engage in a groove or notch 15 which extends transversely across the underside of the drawer 9. In order to check the extension of the drawer 85 at the proper point, and to prevent the drawer from being accidentally withdrawn completely from the incubator, I have provided at each side of the incubator, near the front edge, a spring-pressed pin 16 which is adapted to enter a recess 17 formed in the inner end of the drawer. When it is desired to close the drawer, the pins may be withdrawn from the recesses 17 by means of the protruding heads 18.

Within the drawer 9, a plurality of trays 19 extend transversely thereof and are provided with trunnions 20 which are revolvably supported in vertical slots 21 formed in the inner side walls of the drawer. Each tray is 100 preferably of a width to receive two rows of eggs, and the slots 21 extend to the upper edges of the side walls of the drawer so that the trays may be easily removed therefrom for the purpose of cleaning or filling 105 the same. Each tray is provided at one end with a sprocket wheel 22 which is engaged by a sprocket chain 23, the upper and lower flights of which extend outwardly through slots 24 in the front wall of the 110

drawer and engage over a sprocket wheel 25 which is mounted in a bracket 26 secured to the front side of the drawer. A series of L-shaped brackets 27 or the like are arranged 5 to bear against the upper flight of the chain 23 between the trays to secure proper engagement of the chain with the sprockets 22, and the lower flight of the sprocket chain is supported by a series of rollers 28 for a 10 similar purpose.

It will be understood, therefore, that when the sprocket wheel 25 is rotated through an angle of 180°, all of the trays are turned simultaneously. For convenience in effecting 15 this rotation, I have provided a bail 29 which is secured, by a non-rotatable connection, to the sprocket wheel 25 and may be retained in its upper or lower position by means of holders 30.

For the purpose of inserting or removing 20 the eggs from the trays, each tray is provided with a removable cover 31 which is preferably foraminous so that proper circulation and ventilation will be secured, the bottoms also being foraminous, as shown at 25 55 in Fig. 2. The cover 31 is provided at one end with a plurality of eyes 32 which engage hooks 33 secured in the end wall of the tray. The other end of the cover is provided 30 with a bail 34 which extends around one or more eccentrics 35. Each of these eccentrics is provided with a circumferential groove 36 within which the bail 34 is adapted to be retained, and the eccentric is 35 40 pivotally mounted on a pin 37 about which it may be moved by means of a lug 38, to the position shown in Fig. 3, wherein the cover is stretched and maintained in closed position. The eccentric is also provided with a 45 notch 39 in which a pin 40 may be inserted to lock the eccentric in position, but may be easily removed when it is desired to rotate the eccentric to release the bail 34 and remove the cover. A retaining rod 41 may 50 also be extended transversely across the cover to retain the intermediate portion of the same in proper position when the tray is inverted, and this retaining member is provided at its ends with eyes 42 which slidably engage the tracks 43 that extend from end 55 to end of the tray and are preferably secured intermediately to the sides of the tray, as indicated at 44. When it is desired to remove the cover, the retaining rod 41 may be moved to the end of the tray, and the cover, after being released by the eccentrics 35, may be easily removed.

The incubator is preferably provided with 60 a ventilating hole 45 in its rear wall which may, if desired, be closed by a removable peg. A thermometer tray 46 may also be secured at a convenient point along the side wall where it may be viewed through a small window 47.

For supporting the lamp 4, I have provid-

ed a U-shaped bracket 48 which is secured by screws to the under wall of the body 1, as shown in Fig. 6, and a vertical screw-threaded rod 49 is adjustably supported in the bracket by means of suitable lock nuts 50, and its upper end is guided in a plate 51 secured between the legs of the bracket, and the upper end of the rod projects into a recess 52 formed in the bottom of the body 1. The lower end of the rod 49 is provided with 75 an adjustable wing nut 53 or the like by means of which the lamp support 54 may be adjustably supported.

From the foregoing description, it will be seen that I have provided an incubator in 80 which the turning and cooling of the eggs, or any of the other operations which are necessary in using the incubator, may be performed with very little labor and in a minimum amount of time, all of the eggs 85 being handled simultaneously. The eggs may be supported in the drawer and cooled without removing the same therefrom. It will also be noted that when the drawer is in its extended position, the inner end thereof will close the opening into the incubator and thus prevent the interior thereof from becoming cooled. The lamp may be easily and quickly adjusted vertically in 90 order to obtain the best results.

While I have shown and described in detail the construction and arrangement by means of which my invention may be carried out, it will be understood that this is merely illustrative and that various modifications may be made in the details thereof 100 without departing from the spirit of the invention as defined by the claims.

What is claimed is:

1. In an incubator, an egg chamber, a 105 plurality of trays in said chamber for receiving eggs, each tray having trunnions on which it is revoluble, and a sprocket wheel secured thereto, a sprocket wheel revolvably mounted outside the chamber, a sprocket chain connecting all of said sprocket wheels, a bail secured to the outside sprocket for oscillating the same to turn the trays, and means for limiting the movement of the bail 110 in each direction.

2. An egg tray for incubators, comprising 115 bottom and side walls, a foraminous cover hinged at one end and having a bail at the other end, and a rotatable eccentric for engaging said bail to hold the cover in closed position.

3. In an incubator, a tray adapted to be filled with eggs and having a cover, hooks at one end of the tray, eyes on one end of the cover engaging the hooks, the other end of the cover having a bail, eccentrics mounted on the tray and having circumferential grooves with which the bail is engageable, said eccentrics being rotatable to lock the bail in the grooves or release it therefrom. 125 130

4. In an incubator, a tray adapted to be filled with eggs and having a removable foraminous cover supported at each end, tracks secured to the tray at each side of the cover, and a retaining member slidably supported by the tracks and normally extending across the intermediate portion of the cover to retain and support the same when the tray is inverted, said retaining member being slidable longitudinally beyond the end of the cover to permit the cover to be removed when the bail is released from the eccentrics.

5. In an incubator, a tray adapted to be filled with eggs and having a cover, hooks

15 at one end of the tray, eyes on one end of the cover engaging said hooks, the other end of the cover having a bail, eccentrics mounted on the tray and having circumferential grooves with which the bail is engageable, said eccentrics being rotatable to lock the bail in the grooves or release it therefrom, tracks secured to the tray at each side of the cover, and a retaining member slidably supported by the tracks and

25 normally extending across the intermediate portion of the cover to retain and sup-

port the same when the tray is inverted, said retaining member being slidable longitudinally beyond the bail at the end of the cover to permit the cover to be removed 30 when the bail is released from the eccentrics.

6. In an incubator, an egg tray having a foraminous cover with eyes at one end, hooks secured to the side of the tray and on which the eyes are mounted, the other end of the cover having a bail, and eccentrics mounted on the tray and having circumferential grooves with which the bail is engageable, said eccentrics being rotatable to lock the bail in the grooves or release it there- 35 from.

7. In an incubator, an invertible tray having a foraminous cover hinged at one end, said cover having a bail at the other end, and an eccentric rotatably mounted on the side of the tray and engageable with said bail to hold the cover in closed position.

In testimony that I claim the foregoing as my own, I have hereunto affixed my signature.

PEHR CHRISTIANSSON.
